UNITED STATES PATENT OFFICE

149,290

DESIGN FOR A VEGETABLE AND FRUIT
PEELER

Laura R. Meyran, Fresno, Calif., assignor of one-half to Sterling N. Schein and Forrest Lark, both of Fresno, Calif.

Application September 16, 1946, Serial No. 133,354

Term of patent 3½ years

(Cl. D22—3)

To all whom it may concern:

Be it known that I, Laura R. Meyran, a citizen of the United States, residing at Fresno, in the county of Fresno and State of California, have invented a new, original, and ornamental Design for a Vegetable and Fruit Peeler, of which the following is a specification, reference being had to the accompanying drawing, forming part thereof.

I claim:

The ornamental design for a vegetable and fruit peeler, as shown.

LAURA R. MEYRAN.
